UNITED STATES PATENT OFFICE.

CHARLES L. GANNAWAY, OF CHATTANOOGA, TENNESSEE.

VALVE AND VALVE-SPRING REMOVER.

1,266,788.

Specification of Letters Patent. Patented May 21, 1918.

Application filed January 29, 1918. Serial No. 214,354.

To all whom it may concern:

Be it known that I, CHARLES L. GANNAWAY, a citizen of the United States, residing at Chattanooga, in the county of Hamilton 5 and State of Tennessee, have invented new and useful Improvements in Valves and Valve-Spring Removers, of which the following is a specification.

This invention relates to a tool for use in 10 lifting and removing the valve springs and valves of internal combustion engines.

The object of the invention is to provide a device of this character of improved construction to engage valve rods and valve 15 springs of different sizes, and embodying means for lifting the valves and removing the springs with greater ease and facility.

Another object is to provide an improved construction of tool with adjustable jaws 20 and means for quickly and conveniently adjusting the same.

With these and other objects in view, the invention consists of the features of construction, combination and arrangement of 25 parts, hereinafter fully described and claimed, reference being had to the accompanying drawing, in which:—

Figure 1 is a view in side elevation of my improved valve and valve spring remover.

Fig. 2 is a top plan view of the same.

Fig. 3 is a vertical transverse section through the tool on line 3—3 of Fig. 1.

Fig. 4 is a vertical transverse section through the upper lever on line 4—4 of 35 Fig. 1.

In carrying my invention into practice I provide a tool of the character described comprising a pair of superposed levers 1 and 2 terminating at their rear end in handles 3 and 4. These levers are pivotally connected at a point between their transverse centers and forward ends, to permit said forward ends of the levers to be adjusted toward and from each other, as well 40 as to permit of the forward end of the upper lever being independently operated, for purpose hereinafter described. As shown in the present instance the pivotal connection comprises a pivot lug 5 extending upwardly from the lever 1 and disposed be-

tween a pair of pivot lugs 6 depending from the lever 2, said lug being connected by a headed transverse pivot pin 7 held in position by a cotter pin or retaining key 8. The lugs 6 are spaced a greater distance than the 55 width of the lug 5, as will be evident by reference to Fig. 3.

The forward end of the lever 1 is in the form of a comparatively wide plate which is forked to provide a pair of opposed jaws 9, said jaws being rigid with said lever and offset laterally beyond the plane of the lever to form a wide surface to engage and bear upon the lower end of the valve spring. The upper surfaces 10 of the jaws 9 are 60 beveled to form inclined planes so that the jaws may be readily inserted under the lower convolution of the spring, so as to permit the valve stem or tappet rod to enter the space between said jaws, as will be 65 readily understood.

The forward end of the lever 2 is also forked to provide a pair of jaws 11. These jaws are also offset laterally beyond the plane of the lever 2 to form a wide bearing 75 for engagement with the upper convolution of the spring and are rabbeted at their upper sides along their inner faces to form inwardly projecting flanges 12 of less thickness or depth than the jaws, so that they may be 80 freely inserted between convolutions of a spring, and the spring securely retained in engagement therewith. The walls of the rabbets are formed to provide straight side walls or surfaces 13 and curved rear walls 85 or shoulders 14, said walls operating to hold the coils of a spring seated on the flanges from having lateral motion and from springing out rearwardly beyond the curved shoulders, such shape and construction of 90 the jaws 11 insuring the firm retention of the spring engaged thereby.

The lever 2 is bifurcated or longitudinally slotted, as shown at 15, the slot extending forwardly through and intersecting the space between the jaws 11 and also extending rearwardly of the pivotal connection between the jaws. By this construction a pair of spring arms 16 are formed, which respectively carry the opposed jaws 11 at 100

their forward ends, and which permit of the adjustment of said jaws 11 toward and from each other. By this means the distance between the jaws may be regulated, to adapt 5 the device for application to valve stems and springs of different diameters, as well as to adapt the upper jaws to be engaged with valve seat guides when necessary for the purpose of bringing the jaws 11 into bearing engagement with the upper convolution of the spring.

The arms 16 are adapted to be adjusted toward and from each other for the purpose of adjusting the jaws 11, such adjusting 15 movement of the arms 16 being permitted by the loose pivotal connection afforded by spacing the lugs 6 a greater distance apart than the width of the lug 5, as described. For the purpose of adjusting the arms 16 an 20 adjusting device is provided, comprising a shaft 17 having right and left hand threaded ends 18 and 19 which work in correspondingly threaded openings 20 in bearing pins 21. The bearing pins 21 are fitted in vertical openings 22 formed in offsets 23 carried by the arms 16, and said offsets and arms are formed with openings 23' through which the threaded ends of the shaft extend more or less loosely, thus allowing the bearing 25 pins or bushings 21 to have a slight degree of pivotal play, to permit the arms 16 to be adjusted inwardly and outwardly. At the center of the shaft is an angular head or portion 24 which may be employed as a finger piece or to which a wrench or similar tool may be applied for the purpose of adjusting the shaft, as will be readily understood.

It will be understood that by means of the 40 pivotal connection the sets of jaws carried by the levers 1 and 2 may be moved vertically toward and from each other by manipulating the handles 3 and 4. Thus the distance between said sets of jaws may be varied as 45 desired according to the length of the spring which is to be engaged. The jaws 9 of the lower lever 1 may also be arranged to embrace the tappet rod and bear upon its guide as an abutment, while the jaws of the lever 2 50 are engaged under the collar or washer at the base of the spring and said jaws of the upper lever forced upwardly by depressing the handle 4, thus enabling a large degree of power to be applied to lift or compress 55 the valve spring for removal of the cotter pin or fastening so that the spring may be readily removed and the valve lifted.

A locking means is provided for holding the two levers in adjusted position by spacing 60 the sets of jaws at the required distance apart. This locking device comprises a latch member 25 pivoted at its lower end to a lug 26 on the lever 1 and extending up-

wardly through the slot 15 in the lever 2. The upper end of this latch 25 is formed to 65 provide a bearing surface 26' for engagement with the thumb or finger of the hand holding the tool, whereby the latch may be swung forwardly to unlocking position. A spring 27 connects the latch with the handle 70 3 and serves to normally swing it rearwardly to locking position. On the rear face of the latch is a longitudinal series of locking teeth 75 28 adapted to engage a locking tooth or shoulder 29 formed by beveling the rear end wall of the slot 15, whereby the lever 2 may be locked in any desired position in its range of movement relative to the lever 1.

Having thus fully described my invention, I claim:

1. A tool of the character described comprising a pair of superposed pivoted levers having forked ends forming superposed pairs of jaws, the upper lever of the pair being longitudinally bifurcated to form 85 spring arms carrying the jaws thereof, and means adjustably connecting said arms for moving the jaws thereof toward or from each other.

2. A tool of the character described comprising a pair of superposed levers pivotally connected at a point between their transverse center and forward ends, said levers having handles at their rear ends and being forked at their forward ends to form 95 pairs of superposed jaws, the upper lever being longitudinally slotted to provide spring arms carrying the jaws thereof and extending in front and rear of the pivotal connection, and means adjustably connecting said 100 arms.

3. A tool of the character described comprising a pair of superposed levers, said levers having forked forward ends forming pairs of superposed jaws, the upper lever being longitudinally slotted to provide spring 105 arms carrying the jaws thereof, a loose pivotal connection between the arms of the upper lever and the lower lever adapted to permit movement of the jaws toward and from each other, and means for connecting the arms for relatively adjusting the same.

4. A tool of the character described comprising a pair of superposed pivoted levers having forked forward ends forming jaws, the upper lever being longitudinally slotted to provide spring arms carrying the jaws thereof, bearing bushings mounted in said arms and having threaded transverse openings, and an adjusting shaft having reversely threaded end portions passing through and adjustably engaging the threaded openings in the bushings.

5. A tool of the character described comprising a pair of superposed pivoted levers 125 having forked forward ends forming super-

posed pairs of jaws, the upper lever being longitudinally slotted to provide spring arms carrying the jaws thereof, the rear wall of the slot forming a locking tooth, means ad-

5 justably connecting the spring arms of the upper jaw, and a spring actuated locking element pivoted to the lower lever and ex-

tending upwardly through said slot in the upper lever and provided with locking teeth to engage said locking tooth of the upper 10 lever.

In testimony whereof I affix my signature.

CHARLES L. GANNAWA.
